Primary Examiner — Carol P Rademaker(74) *Attorney, Agent, or Firm* — Stephen J. Weyer; Stites & Harbison PLLC(57) **CLAIM**

The ornamental design for a perfume bottle, as shown and described.

DESCRIPTION

FIG. 1 is a front view of a perfume bottle showing the new design.

FIG. 2 is rear view thereof.

FIG. 3 is a left side view thereof.

FIG. 4 is a right side view thereof.

FIG. 5 is a top view thereof.

FIG. 6 is a bottom view thereof; and,

FIG. 7 is a front, top and left side perspective view thereof. The dash-dash-dash broken lines shown in the FIGS. 1-5 & 7 drawing views are included for the purpose of illustrating environmental structure and form no part of the claimed design.

The dot-dash-dot-dash broken line shown in the FIG. 6 drawing view defines the bottom boundary of the claimed design.
